Inventor

Baltus DeLong,

United States Patent Office.

BALTIS DE LONG, OF WASHINGTON, DISTRICT OF COLUMBIA.

Letters Patent No. 85,915, dated January 19, 1869.

IMPROVEMENT IN MUCILAGE-BOTTLES.

The Schedule referred to in these Letters Patent and making part of the same.

To all whom it may concern:

Be it known that I, BALTIS DE LONG, of Washington city, in the District of Columbia, have invented a certain new and useful Apparatus for Gummimg or Pasting Papers, Labels, and other similar articles, of which apparatus the following is a full, clear, and exact description.

My invention is more particularly adapted to gumming the edges of papers which are intended to be pasted together or into a book. It may also, however, be adapted to pasting entire sheets, by increasing the dimensions of the respective parts.

The improvements herein claimed consist—

First, in a novel method of combining, with a receptacle or reservoir for the paste or mucilage, a gumming-apparatus, mounted in an independent frame, which is fastened in the reservoir by the mere act of inserting it, and yet can readily be removed therefrom when desired.

Second, in a novel method of combining a frame, a pasting-roller, and a guide, which clamps the paper and holds it upon the roller while being pasted.

Third, in a novel method of combining the frame, the pasting-roller, and the clamping-guide, with a gauge for adjusting the width of the strip pasted.

Fourth, in a novel method of combining, with the frame and pasting-roller, a compressing-roller, rotating at an acute angle to the line of feed, to keep the paper against the gauge.

In the accompanying drawings, which show all my improvements embodied in one apparatus—

Figure 1 represents a view in elevation of my improved apparatus, showing two different modifications of my invention.

Figure 2 represents a similar view of the apparatus taken at right angles to fig. 1, and showing a front view of the device on the right of fig. 1.

Figure 3 represents a similar view of the other device.

Figures 4 and 5 are respectively plan views of the rollers detached, showing the angular arrangement of the axes of the upper rollers.

To carry out the objects of my invention, I construct a reservoir or receptacle, A, of metal, glass, or other suitable material, and of proper form, with a flanged opening, a', in its top. This opening I make of an oblong or oval form, with an enlargement in its centre, as shown in figs. 1 and 2, for a purpose hereinafter explained.

The pasting-apparatus is mounted in a frame, A', by preference cut or stamped from sheet-metal, and of the form shown in figs. 1 and 2, consisting of a strip, continuous on one side, and bent over in a rectangular form at top and bottom, so as to form bearings for the rollers, and yet leave an open space between them on one side.

The upper, or compressing-roller B, is mounted in a supplementary frame, b, enclosed within the main frame A', and suspended from it by an arm, c.

This roller is depressed, when desired, by a button, d, on this arm, but ordinarily is held up by a spring, c', in this instance, of rubber.

It is, however, obvious that a metal spring might be coiled around the shank of the button, between it and the frame A', to hold up this roller.

The journals of the roller project through vertical slots, c', in the frame A', by which means the roller, while free to move vertically, is prevented from yielding laterally. The axis of this roller is arranged angularly to that of the lower roller, as shown in fig. 4, for a purpose hereinafter explained.

The gumming-roller B', is mounted in bearings in the lower part of the frame. I prefer to make this roller in the form of a thin disk internally, but with a broad rim or tread, so that while presenting the desired amount of pasting-surface, its displacement shall be as small as possible. The sides of the frame may be bent outward, above the axle of this roller, to prevent paste dropping from the roller and clogging the frame.

I form slight grooves in the gumming-roller, either parallel or transverse to its face, in order to retain paste enough to gum the sheet while passing under the compressing-roller, which, otherwise, I find by experiment, tends to drive back the paste on the roller, and thus prevent its proper disposition on the sheet. The pasting-roller, however, need only be grooved on those parts acted upon by the pressure-roller.

In order to present the paper to the rollers, and to guide it properly, I form a clamping-guide, C, by bending a wire into a loop, and passing the loop through holes in the frame.

A wedge, f, fig. 1, is inserted into this loop, and regulates the pressure of the loose ends of the wire on the sheet, by opening or closing the loop.

A gauge, C', slides upon the wire clamp, to regulate the width of the strip inserted between the rollers, and may be held in the desired position in any proper, well-known way.

The frame A' is provided with clips, a', which spring over the edges of the flanged opening a', and hold it firmly when inserted, and yet permit it to be removed without detaching-screws or other fastenings.

The operation is as follows:

The operator depresses the compressing-roller by bearing on the button d, with his left hand, until it presses on the pasting-roller. As soon as the rollers B B' are in contact, he turns the compressing-roller until the gummed surface of the pasting-roller comes up. Before, however, the gummed surface comes in contact with the compressing-roller, the sheet is inserted between the rollers, with the side to be gummed next the pasting-roller, where it is held by the clamping-guide and the gauge.

With the clamping-roller still depressed by his left hand, the operator rotates the compressing-roller, which draws the sheet through, at the same time revolving the pasting-roller, which gums the sheet uniformly. As soon as the sheet has passed through the rollers,

the compressing-roller is released, and its spring lifts it out of contact with the pasting-roller, thus preventing paste from getting on both rollers, and gumming both sides of the succeeding sheet.

The apparatus may be removed, when desired, and a wide brush, with its handle inserted in a cover, may be used instead, when desired, or, by having two openings, both may be used at once.

In fig. 3, I have shown the apparatus as modified, by substituting an endless belt, E, for the pasting-roller.

This belt passes over two rollers, D D'. The upper roller, D, is mounted in proper bearings, and provided with a crank for driving it, the compressing-roller, in this instance, being the one driven by friction, instead of the pasting-roller, as in fig. 2.

The lower roller turns in bearings, in strips e, fastened to a block, E', which is adjustable vertically in the frame by a slot and set-screw, f'. This block acts as a brace to the frame, and also serves to tighten the belt.

The angular arrangement of the compressing-rollers, shown in figs. 4 and 5, serves to draw the edge of the

sheet inwards, and thus keeps the edge of the sheet constantly pressed against the gauge, and thus insures uniform work.

What I claim as my invention, and desire to secure by Letters Patent, is—

1. The combination, with a mucilage-receptacle, of a gumming-apparatus, mounted in an independent detachable frame, substantially as and for the purposes specified.

2. The combination, substantially as set forth, of the frame, the pasting-roller, and the clamping-guide.

3. The combination, substantially as set forth, with the frame, pasting-roller, and clamping-guide, of a gauge for adjusting the width of surface gummed.

4. The combination, substantially as set forth, with the frame and the pasting-roller, of an angularly-arranged compressing-roller, whereby the material being gummed is kept in contact with the gauge.

BALTIS DE LONG.
